UNITED STATES PATENT OFFICE

GERNOT W. HEINEMANN AND ARTHUR HEINEMANN, OF BELLINGHAM, WASHINGTON;
ARTHUR HEINEMANN ADMINISTRATOR OF ESTATE OF SAID GERNOT W. HEINEMANN, DECEASED

BOAT CONSTRUCTION

Application filed April 6, 1931. Serial No. 528,174.

This invention relates to a boat construction, the general object of the invention being to form a light-weight boat of strong structure by forming the frame of the boat of 5 aircraft tubing or channel steel, all parts of which are welded together with the planking fastened to the frame with self tapping sheet metal screws and the framing being connected at the sides to metal members which act to 10 stiffen the boat longitudinally and also act to support a coaming in a water proof manner.

Another object of the invention is to provide a waterproof flooring in the lower part 15 of the boat which forms with the bottom part of the boat an air chamber which may be divided into compartments by waterproof bulk heads so as to prevent the boat from sinking when damaged below the water line.

This invention also consists in certain other features of construction and in the combination and arrangement of the several parts, to be hereinafter fully described, illustrated in the accompanying drawings and 25 specifically pointed out in the appended claims.

In describing the invention in detail, reference will be had to the accompanying drawings wherein like characters denote like or 30 corresponding parts throughout the several views, and in which:—

Figure 1 is a perspective view of the frame of the boat constructed in accordance with this invention.

Fig. 2 is a transverse sectional view 35 through a round bottom boat.

Fig. 3 is a section on the line 3—3 of Fig. 2.

Fig. 4 is a detail view of a portion of one 40 side of the boat showing how a longitudinally extending member is connected with one of the side members of the frame.

Fig. 5 is a sectional view through the stem of the boat.

Fig. 6 is a side view of the stem member.

Fig. 7 is a view similar to Fig. 2, but showing a flat bottom boat with the framing formed of channel steel.

Fig. 8 is a section on the line 8—8 of Fig. 7.

As is shown in these drawings, the frame

assembly A of the boat is built of steel or other tubing 1, as shown in Figs. 1, 2, 3, 4 and 5 or of channel steel 3 as shown in Figs. 7 and 8. The parts are all welded together or brazed or connected by gusset plates and 55 bolts where necessary.

As shown in Fig. 1, the frame A is composed of a plurality of transverse members B which are connected together by a keel 4 which passes through recesses 5 formed in 60 the central portion of the bottom part of the members and the upper ends of each of the members B is bent inwardly as shown at 6 and connected to the longitudinal members 7 which act as longitudinal stiffening and bracing members, and also as supports for coaming. These members 7 are connected to the side portions of the member B by the diagonal braces 8. These members 7 may extend from 65 the stern frame to the first frame or member 70 B having cross beams for the decking incorporated in its structure, or they may extend throughout the length of the boat in undecked boats.

As shown in Fig. 2, the framing may be 75 shaped to provide a round bottom boat or it may be shaped to provide a flat bottom boat as shown in Fig. 7. It will of course be understood that the framing may be shaped to provide a V-shaped bottom boat or a boat of 80 any other desired shape.

Each member B also includes the cross members 9 which act as supporting means for the flooring 10, and the cross members 9 are braced by the braces 11.

The flooring 10, the planking 12 and the coaming (not shown) are all fastened to the frame by the self tapping sheet metal screws 13, and the flooring, planking and coaming are covered on both sides with airplane fabric treated with aircraft dope to make the 85 fabric waterproof.

As shown in Figs. 2 and 7, the flooring forms a watertight chamber 15 in the bottom of the boat which may be divided into compartments by waterproof bulkheads so as to prevent the boat from sinking if it should be damaged below the water line.

The stem member 16 at its lower end is 95 connected with the front end of the keel 4 100

and said member is formed of tubing 17 or the like, and the wing forming plates 18 welded thereto against which the front ends of the planking rest. The screws 13 which 5 pass through the front ends of the planking also pass through the plates 18 and the tube 17. The nose member 19 is of substantially triangular shape, and abuts the front end of the planking and is fastened to the tube 17 by 10 the sheet metal screws 20.

From the foregoing it will be seen that we have provided a light-weight boat, the framing of which is formed of any suitable metal of tubular, channel or other suitable cross 15 sectional shape, and the parts of which are all welded, brazed or otherwise connected together, the boat being provided with airtight compartments in its lower part to prevent the boat from sinking and all the wooden parts 20 are covered with aeroplane fabric or the like treated with aeroplane dope to prevent dry rot and to make the parts waterproof.

The boat can be constructed at low cost 25 and has great strength and is of light-weight and is thoroughly seaworthy. Each channel member is built up from three strips of sheet steel, the center one straight and bent as needed, and the outer ones cut curved as needed 30 and welded together so as to form a boat rib of the proper shape without necessity for further bending after the strips are welded together. A boat rib of this construction would be as strong as a die stamped one and 35 much easier to make with less expensive equipment.

It is thought from the foregoing description that the advantages and novel features of the invention will be readily apparent.

It is to be understood that changes may 40 be made in the construction and in the combination and arrangement of the several parts, provided that such changes fall within the scope of the appended claims.

Having thus described our invention, what 45 we claim as new is:—

1. A boat of the class described comprising a frame formed of metal parts of hollow cross sectional shape, the joints of which are integrally connected together and said frame 50 including a longitudinally extending member at each side thereof connected with the upper end of the upright portion of the framing, and planking connected to the frame by self-tapping sheet metal screws.

55 2. A boat of the class described comprising a frame formed of metal parts of hollow cross sectional shape, the joints of which are welded or brazed and said frame including a longitudinally extending member at each side welded or brazed to the upper ends of the vertical portions of the frame and braces connecting the longitudinal members of the side members and welded or brazed to the members and longitudinally extending mem- 60 ber.

3. A boat of the class described comprising a frame part formed of metal parts of hollow cross sectional shape, the joints of which are welded or brazed, said frame part including longitudinally extending members at the 70 sides welded or brazed to the upper ends of the side members of the frame part, and said frame part also including cross members, flooring supported by cross members, planking forming the sides of the boat, a coaming supported by the longitudinal members, said flooring, planking and coaming having both 75 sides covered with aeroplane fabric treated with aeroplane dope and the flooring providing a watertight compartment for preventing sinking of the boat.

4. A boat of the class described comprising a frame part formed of metal and including a plurality of spaced transversely arranged members, the upper ends of each of which is bent inwardly, a longitudinally extending member welded or brazed to the ends of the inwardly extending part, brace members for the longitudinally extending members welded or brazed to the said members and to the side portions of the transverse members, a stem member formed of metal of hollow cross sectional shape, metal plates welded or brazed to said hollow member and forming wings, planking forming the sides of the boat and self tapping sheet metal screws connecting the planking to the metal parts with screws at the front end of the planking passing thru the plates and the hollow members.

5. A boat of the class described comprising a frame part formed of metal and including a plurality of spaced transversely arranged members, the upper ends of each of which is bent inwardly a longitudinally extending member welded or brazed to the ends of the inwardly extending part, brace members for the longitudinally extending members welded or brazed to the said members and to the side portions of the transverse members, a stem member formed of metal of hollow cross sectional shape, metal plates welded or brazed to said hollow member and forming wings, planking forming the sides of the boat and self tapping sheet metal screws connecting the planking to the metal parts with screws at the front end of the planking passing through the plates and the hollow members, a keel member passing through the recesses formed in the transverse members and having the front ends connecting with the stem member, cross members forming part of the frame, flooring supported on the cross members and forming an airtight compartment in the bottom of the boat, coaming supported by the longitudinal members, aeroplane fabric covering both faces of the flooring, the planking and the coaming and said fabric being treated with aeroplane dope to render the same water proof.

6. A boat of the class described comprising 130

a frame formed of metal parts of channel shape in cross section welded or brazed at the joints, each member being formed of a bight part bent to the desired shape and a pair of side parts cut to the desired shape and welded to the bight part.

5 In testimony whereof we affix our signatures.

GERNOT W. HEINEMANN.
